Patented Oct. 26, 1971

222,472

PORTABLE DATA COMMUNICATION TERMINAL

Allen G. Jacobson, Ramsey, N.J., assignor to Computer
Transceiver Systems, Inc., Paramus, N.J.

Filed Sept. 4, 1970, Ser. No. 24,833

Term of patent 14 years

Int. Cl. D14—02

U.S. Cl. D26—5

FIG. 1

FIG. 1 is a perspective view of a portable data communication terminal embodying my new design;

FIG. 2 is a view of one side of the terminal of FIG. 1;

FIG. 3 is a view of the other side of the terminal of FIG. 1;

FIG. 4 is a front view of the terminal of FIG. 1 with the case closed;

FIG. 5 is a top view of the terminal of FIG. 1 with the case closed; and

FIG. 6 is a back view of the terminal of FIG. 1 with the case closed.

I claim:

The ornamental design for a portable data communication terminal, as shown.
